UNITED STATES PATENT OFFICE.

FÉLIX AHOND, OF PARIS, FRANCE.

VARIABLE-SPEED GEAR.

1,370,080.

Specification of Letters Patent.

Patented Mar. 1, 1921.

Application filed October 16, 1919. Serial No. 331,170.

To all whom it may concern:

Be it known that I, FÉLIX AHOND, citizen of the Republic of France, residing at 5 Boulevard Ornano, Paris, Seine, in the Republic of France, have invented new and useful Improvements in Variable-Speed Gears, of which the following is a specification.

The present invention consists in the use 10 of one or more planetary rollers held in a supporting frame which is rotated by the source of motive power, the axis of the planetary rollers being simply obliged to remain in a plane passing through the axis 15 of the supporting frame. Under the action of centrifugal or centripetal force, the planetary rollers come in contact by means of their surfaces d^1 and d^2 with two crown pieces, one of which, D^1 , is fixed, while the 20 second, D^2 , is movable about the axis of rotation of the supporting frame (Fig. 1.)

According to the relation which exists 25 between the respective contact diameters d^1 d^2 D^1 D^2 of the rollers and the crown pieces, the rotation of the frame carrying these rollers causes the crown pieces D^2 to rotate in the same or in contrary sense.

By varying any one of the diameters D^1 D^2 d^1 d^2 , or several of these at the same time, 30 the crown piece D^2 is given a rotary movement at various speeds according to the case, and may be brought to a standstill for certain respective values of said diameters.

The annexed drawing shows by way of 35 example several forms of the apparatus. In said drawing:

Figure 1 shows in longitudinal section a device constructed in accordance with the 40 invention;

Fig. 1^a is an end view of the supporting frame;

Figs. 2, 3, 4, 5 and 6 show modifications 45 of the apparatus according to the invention;

Fig. 7 shows another modification together with direct drive.

The variation of the diameter of rolling contact can be obtained in divers ways, either by designing the rollers and crown pieces in conical shape with straight or 50 curved generatrices, in which case the relative displacement of the parts along the axis causes the modification of the diameters of rolling contact (Fig. 2), or by increasing or diminishing the diameter of the crown

55 pieces by the use of various concentric clamping and unclamping devices after the

manner of the chucks employed on machine tools (Fig. 3), or by the stoppage of one of the crown pieces in a series D^1 containing several crown pieces disposed in line 60 (Fig. 4), (in this case the rollers or crowns can be provided with gear teeth), or again, by any other suitable means such as increase or diminution of the diameters of rolling contact by the action of fluids under pressure (Fig. 5).

In all cases in which the two diameters in contact are invariable, the simple rolling contact can be replaced by gear teeth which will act to prevent any possible slipping, 70 and this no longer requires the action of centrifugal force in order to maintain the contact (Fig. 6).

The method shown in Fig. 7 is characterized by the use of a speed variation 75 caused by the longitudinal displacement of the crown piece D^2 , together with a design which allows of automatically separating the planetary rollers from the crown piece D^1 , especially in the case where the position 80 of the crown piece D^2 causes its speed to equal the speed of the supporting frame. In this position, a set of tenons mounted on the supporting frame is made to enter corresponding openings in the crown piece 85 D^2 , and the coupling is now made in a direct manner; the action of the rollers is here suppressed, and the driving shaft is connected directly with the operated shaft.

Having now described my invention what 90 I claim as new and desire to secure by Letters Patent is:

1. A variable speed gear comprising a driving shaft and a driven shaft, planetary rollers having two rolling surfaces, a rotary 95 supporting frame for said rollers fixed to one of the shafts and having radial slots in which the shafts of the roller are slidably mounted, a fixed internally geared member against which one of the rolling surfaces of 100 said rollers rolls, a rotatable internally geared member fixed to the other shaft and against which the other of the rolling surfaces of said rollers rolls and means whereby the ratio of the diameters of rolling contact 105 of the internally geared members and the planetary rollers can be varied.

2. A variable speed gear comprising a driving shaft and a driven shaft, planetary rollers having two rolling surfaces, a rotary supporting frame for said 110 rollers, fixed to one of the shafts and having

radial slots in which the shafts of the rollers are slidably mounted, a fixed internally geared member against which one of the rolling surfaces of said rollers rolls, rotatable internally geared member fixed to the other shaft and against which the other of the rolling surfaces of said rollers rolls, the

said members receiving a conical shape whereby the ratio of the diameters of rolling tools for contact can be varied.

In testimony whereof I have signed my name to this specification.

FÉLIX AHOND.
